UNITED STATES PATENT OFFICE.

JOHN R. HARE, OF BALTIMORE, MARYLAND.

PHONOGRAPH.

SPECIFICATION forming part of Letters Patent No. 678,174, dated July 9, 1901.

Application filed March 26, 1901. Serial No. 52,906. (No model.)

To all whom it may concern:

Be it known that I, JOHN R. HARE, of the city of Baltimore and State of Maryland, have invented certain Improvements in Phonographs, of which the following is a specification.

The object of the present invention is to protect phonograph-records against injury by handling and in transporting and storing the same; and the said invention consists in inclosing a record in a casing, in which it may rotate freely, the said casing having a slot through which the style passes to contact with the record.

15 In the further description of the said invention which follows, reference is made to the accompanying drawings, forming a part hereof, and in which—

20 Figure 1 is a top view of certain parts of a phonograph embodying the present invention. Fig. 2 is an enlarged partly-sectional side view of the record, its casing, core, and shaft. Fig. 3 is a cross-section taken on the dotted line A A of Fig. 2 and looking in the 25 direction indicated by the arrow.

Referring now to the drawings, 1 is the bed of the phonograph, and 2 the shaft of the record, one end of which is adapted to enter and be secured so as to turn with the sleeve 8, 30 which rotates in the bearing 3.

35 4 is a driving-pulley on the sleeve 8, and 5 a train of gearing which transmits rotary movement from the sleeve 8, carrying the shaft 2, to the feed-screw, (not shown,) which screw, as in ordinary cases, is inclosed within a sleeve 6, along which the sound-reproducer traverses and which is slotted at its under side in order that a segmental nut (not shown) may be brought into contact with the said 40 screw. The casing containing the diaphragm is denoted by 7, and the nozzle to which the horn is attached by 9.

45 Referring now particularly to Figs. 2 and 3, it will be seen that the record, which is denoted by 10, is secured to the core 11, which

is preferably of wood and which in turn is fastened to the shaft 2, and that the whole is placed within a casing 12, having the style-slot 13, the heads 14 of which serve as bearings for the said shaft. In order to prevent the record being burst by unequal expansion of the wood and composition from which the record is made, I interpose between the core and the record an annulus 15 of some slightly-compressible substance, such as paper. 50

It is necessary that the casing 12 should be held stationary when the instrument is in operation, and to this end I preferably notch the casing at 16, and provide some fixed part of the apparatus with a lock 17, adapted to 60 enter the said notch, as shown in Fig. 1.

From the foregoing description it will be understood that each record is contained within a casing, from which it is unnecessary to remove it, that with the protection described records of much greater length than those ordinarily used may be employed, and that the records cannot be injured by ordinary handling.

I claim as my invention—

1. In combination with a phonograph-record, and a shaft to which it is secured, a casing for the said record adapted to be held stationary while the record is in rotation, the said casing being provided with a slot through which the style may pass to contact with the surface of the record, substantially as specified. 70

2. In combination with a phonograph-record and its core, an enveloping casing having a style-slot, which casing is loosely supported from the said core, and adapted to be held stationary when the core and its record are rotated, substantially as, and for the purpose specified. 75

JOHN R. HARE.
